CONTINUOUS PRESS

Charles F. Scherer, Davenport, Iowa

Application April 6, 1936, Serial No. 72,879

11 Claims. (Cl. 100—38)

This invention relates to presses, and has to do with presses of the rotary or continuous type in which two oppositely inclined rotating discs act upon the material being operated upon.

5 Presses of the general type above referred to are known in the art. In the known presses the discs exert maximum pressure upon the material throughout an extremely limited area and may be considered, with respect to maximum pressure, as having line contact only with the material. Presses of this type may be employed for treating various semi-solid materials, such as brewer's grain, beet pulp, wood pulp, and many other materials from which it is desired to remove the bulk of the water or moisture preliminary to drying. Brewer's grain and many other materials, when in a wet condition, particularly if a larger proportion of water than usual is present, are slippery and, when subjected to pressure between the discs, are readily displaced, with the result that no effective pressing operation is exerted upon the material, in many instances, if the moisture content thereof is excessive. In such case, the press is incapable of 15 performing its intended function.

My invention is directed to the provision of a press which avoids the above noted objections to known presses of this type, above referred to, and is capable of handling relatively large quantities of materials. A more specific object is to provide means whereby the material is confined in a closed compartment in such manner as to eliminate possibility of the material, during the pressing operation, flowing either radially or circumferentially of the discs. Further objects are the provision of improved means for mounting the strainer plates upon the discs in such manner as to facilitate removal and replacement thereof, the provision of strainer plates so formed and disposed that the material is subjected to maximum pressure between the discs throughout an area of considerable extent, and the provision of means whereby the speed of rotation of the discs may be varied to suit operating conditions. Further objects and advantages of my invention will appear from the detail description.

In the drawings:

Figure 1 is an isometric front view of a press embodying my invention, showing the driving mechanism and associated parts;

Figure 2 is an isometric back view of the press and associated driving mechanism and parts;

Figure 3 is a transverse vertical sectional view 55 through the press, on an enlarged scale, taken

substantially on line 3—3 of Figure 4, certain parts being shown in elevation;

Figure 4 is a central vertical sectional view taken through the press from front to back thereof, partly broken away, on a reduced scale 5 relative to Figure 3;

Figure 5 is a fragmentary underneath view of the press discs and associated parts, the casing being omitted, on an enlarged scale relative to Figure 4;

Figure 6 is an inner face view of one of the casing sections, the circumferential wall thereof being shown in section, on a reduced scale, and parts being broken away;

Figure 7 is a development, in section, of the 15 cam track of the casing section shown in Figure 6;

Figure 8 is an inner face view, on an enlarged scale relative to Figure 4, of one of the strainer plates, the screen thereof being partly broken 20 away; and

Figure 9 is a fragmentary outer face view of the strainer plate of Figure 8.

The press comprises a casing 10 formed of two opposed cup-shaped sections 11 increasing 25 in depth from top to bottom. Each section 11 is provided, centrally thereof, with a hub 12 having formed integrally therewith an inwardly projecting bearing sleeve 13, the outer portion of which is disposed in concentric spaced relation 30 to the hub. Hub 12 and sleeve 13 are inclined upwardly and inwardly of casing 10, the hub and the sleeve at one side of the casing being inclined oppositely to the hub and the sleeve at the other side thereof. The casing sections 11 35 are secured together in any suitable manner, conveniently by bolting.

A cast iron bushing 14 is disposed about each sleeve 13 and extends within a flanged bronze bushing 15 suitably secured, as by screws 16, to 40 an outwardly extending elongated hub 17 of a conical pressure disc 18. Bushing 15 extends within hub 17 between the latter and bushing 14, as shown. The discs 18 are thus rotatably mounted within the casing 10, are opposed and 45 are oppositely inclined.

A tapered spacing ring 19, conforming in taper to the inclination of the discs 18, is disposed between the central portion of the discs, this ring being provided, at its inner portion, with 50 lateral flanges 20 which seat in annular recesses in webs 21 of sleeve 13, to which webs the ring 19 is secured, conveniently by means of cap screws 22 passing through webs 21 and screwing into lugs 23 formed integrally with flanges 20 at 55

the lower portion of ring 18. The latter thus serves to space the discs 18 properly and is fixed to webs 21 of sleeves 13 so as to be held against rotation. Sealing rings 24 are suitably secured, conveniently by means of screws 28, to the inner ends of the hubs 17 of the discs. The outer peripheries of rings 24 are beveled, the inner ends of disc hubs 17 being provided with annular recesses having surfaces beveled similarly to and constituting continuations of the beveled surfaces of the rings 18, as shown. Each ring 24 is further provided, at its inner periphery, with an angular flange 26 which has bearing upon flange 28 of ring 18 and extends between the latter flange 15 and the inner end of sleeve 13. It will also be noted that the outer portion 17a of hub 17 of the disc is thickened, and has bearing in hub 12 of casing section 11. A thrust ring 27 is disposed within hub 12 between the outer end thereof and the flange of bushing 15. Adjusting screws 28 are threaded through the outer end of hub 12 and bear against the outer face of ring 27. This provides means whereby the disc 18 may be adjusted inward of the casing so as to assure sealing contact between spacing ring 18 and the sealing rings 24, while also providing a highly efficient mounting for the respective discs for reducing tendency to tilt or rock thereof, while preventing objectionable wear of parts.

30 The outer ends of sleeves 13 are closed by flanged discs 30 which fit snugly into the sleeves, these discs being secured in position by a tie rod 31 passing therethrough and having nuts 32 screwed upon its ends and bearing against the outer faces of discs 30, webs 21 of sleeves 13 being provided with central openings 33 which accommodate rod 31. Tubes 34 pass through discs 30 and thread into elbows 35 which screw into sleeve 13 and are connected, by ducts extending therefrom through sleeve 13 and bushing 14, to the bearing surfaces of the bushings 14 and 15. Fittings 36 are mounted upon the outer ends of tubes 34 for supplying lubricant through the latter to the bearing surfaces. These fittings 36 are of known type and need not be illustrated nor described in detail. Tubes 37, provided at their outer ends with fittings 38, extend through discs 30 and webs 21 of sleeve 13, and are connected by elbows 39 and associated ducts to the bearing surfaces of sealing rings 24 and spacing ring 19. I also provide fittings 40 screwed into hubs 12 and connected by ducts 41 to the bearing surfaces between the outer end portions 17a of disc hubs 17 and the inner surface of hubs 12 of the casing 10. In this manner the various bearing surfaces may be lubricated with expedition and facility as required. It will be noted that flange 26 of each of the sealing rings 24 terminates short of the inner face of web 21 of sleeve 13, providing an annular channel 42 at the inner face of the web, the latter being provided with ducts 43 opening into this channel. Any liquid which may leak past the sealing rings 24 flows into channel 42 and thence through ducts 43 into sleeve 13. The latter is drained by means of an elbow 44 screwed into disc 30, at the lowermost point thereof within the circumference of the outer end of the sleeve, this elbow being in register with an opening 45 in the disc. I thus provide means for adequate lubrication of the various bearing surfaces while also assuring proper drainage of any liquid which may leak about the sealing ring 24. This eliminates possibility of liquid which leaks past the sealing rings 24 having access to the bearing

surfaces between the bushings 14 and 15, with consequent washing out of lubricant from between these surfaces.

Each of the pressure discs 18 is provided, at its outer face, with a concentric flange 46 conveniently formed integrally therewith. A ring gear 47 is suitably secured upon flange 46, this ring gear being provided with an inwardly projecting flange 48 which extends across the outer edge of flange 46. Thrust rollers 49 (Figures 1 and 2) are rotatably mounted upon casing 10 adjacent the lower portion and at opposite sides thereof, and project through openings 50 in the casing, within which they bear against flanges 48 of the ring gears 47. The minimum distance between the discs 18, during rotation thereof, is at the lower portion of the discs, as shown in Figure 3, and the rollers 49 serve to take the outward thrust of this portion of the discs in the final stages of the pressing operation, thus effectively holding the discs against outward movement and preventing subjecting of the discs and associated parts to excessive stresses and possible breakage, such as would occur were not these rollers provided. Thrust rollers of this general type are known in the art and need not be illustrated nor described in greater detail, it sufficing to state that such rollers are provided and have associated therewith adjusting means for moving them to and from the discs as required. The water or other liquid pressed from the material passes through the discs 18 and flows into the lower portion of casing 10, from which it escapes through openings 51 through the bottom of the casing, shown in Figure 3, and, in part, through openings 50 if the openings 51 prove inadequate. The liquid flows into a suitable receptacle or trough 52 supported beneath the press upon a base frame 53, the latter also supporting the press. The receptacle or trough 52 is provided with a suitable discharge opening 54.

Referring to Figures 1 and 2, a supporting frame 55, of suitable type, is mounted upon base frame 53 adjacent one side of the press. An electric motor 56 is mounted upon frame 55, at the lower portion thereof, and has sprocket and chain drive connection 57 to a variable speed transmission unit 58 of known type mounted upon the upper portion of frame 55. Any suitable known variable speed transmission may be used, within the scope of my invention.

The transmission unit 58 has driving connection, through a suitable coupling 59, to a speed reducing unit 60 also mounted upon the upper portion of frame 55. The latter unit has driving connection, through a coupling 61, to a drive shaft 62 rotatably mounted through bearing sleeve 63 carried by the casing sections 11. Pinions 64 are keyed upon the ends of shaft 62 and mesh with gears 65 keyed upon a countershaft 66 rotatably supported in bearing sleeves 67 carried by the casing sections 11 below and adjacent sleeves 63 (Figure 4). Pinions 68 are keyed upon countershaft 66, project through openings 69 in casing sections 11 (Figure 3) and mesh with ring gears 47. In this manner the discs 18 may be driven in unison at any desired speed, within limits, to meet requirements. The variable speed drive is highly important and, to my knowledge, is broadly new as applied to a press of this type. In order to assure that the material discharged from the press is in best condition for subsequent treatment, such as drying, it is necessary that the material subjected to pressure at the lower portion of the press contain an adequate pro-

portion of solids. If the material as delivered to the press contains an excessive amount of water or other liquid the press should be operated at relatively low speed so that a considerable portion of the water may drain off through the discs, assuring that an adequate amount of solids is between the lower portions of the discs during the pressing operation. On the other hand, if the material as delivered to the press contains but little or no excess moisture, the proportion of solids being correspondingly high, the press may be operated at relatively high speed. This permits operation of the press at different speeds in accordance with the condition of the material as delivered to the press, which renders it possible to assure that the material as discharged from the press has a substantially uniform moisture content regardless of variations in moisture content of the material as delivered to the press. This is of considerable importance from the practical standpoint as permitting the further treatment of the material, such as drying thereof, to be conducted to the best advantage, thus increasing the rate of production as to the finished material while assuring that the latter will be in a uniform and most desirable condition.

A channel ring 70 fits into each casing section 11 concentrically with disc 18 and is suitably secured in position, as by means of countersunk flat-head screws, as at 71. A sealing ring 72, preferably formed of stainless steel, is mounted in channel ring 70 and has sealing contact with the periphery of disc 18. Ring 72 is split, as shown in Figure 4, and may be adjusted by means of dog-point screws 73 which pass through the wall of casing section 11 and are threaded through channel ring 70. The points of screws 73 engage into recesses in the outer face of ring 72 and the latter may be contracted, by means of screws 73, into sealing contact with the periphery of disc 18 to compensate for wear of the latter. The lateral faces of ring 72 have sealing contact with the flanges of channel ring 70, the latter and the sealing ring 72 thus cooperating to prevent objectionable leakage between the casing section and the disc at the periphery of the latter, and eliminating possibility of escape, at this point, of any of the solid material from between the discs.

The casing sections 11 are provided, at the upper portion of each, with upwardly projecting flanges 75 cooperating to define a rectangular inlet opening 76 for delivering the material between the discs 18 at the upper portion of the press. A delivery hopper 77 seats upon and is bolted to flanges 75, this hopper being provided at its upper end with a flange 78. The latter flange, in practice, may be bolted to the lower end of a valve controlled conduit or chute leading from a bin or other suitable source of supply, by means of which the material to be operated upon is delivered to hopper 77 and thence through opening 76 into the press. The hopper 77 has its inner or back wall extended downward to provide a partition member 79 which extends downward to the spacing ring 19, this member conforming to the space between the discs and serving effectively to close such space. Each casing section is further provided with an outwardly projecting flange 80 extending downward from flange 75, the flanges 80 defining an opening 76a of less area than and extending downward from opening 76. Opening 76a normally is closed by a door 81 provided with lateral flanges 82 which fit within the flanges 80, this door also being provided with a suitable handle 83. A rod 84 is

inserted through flanges 82, adjacent the upper end of door 81, this rod also passing through flanges 80. Door 81 is further provided with an upwardly extending flange 85 of considerable width, which is suitably secured, as by means of cap screws 86, to the lower portion of the front wall of hopper 77. By removing door 81 access may be had to the space between the discs 18, and by removing this door and the hopper 77 an opening of considerable extent is provided at the upper portion of the casing, through which opening the strainer plates of the discs may be removed and replaced, as will be more fully explained presently.

Each casing section 11 is provided, at the opposite side of the axis of casing 10 from hopper 77, with an outwardly extending flange 90 of approximately elongated U-shape. These flanges 90 define an outlet or discharge opening 91 tapering in width downward of casing 10. Conveniently, flanges 90 are suitably bored and tapped for reception of cap-screws by means of which a chute or other suitable conduit may be attached to the flanges in position to receive material discharged through the opening 91, for the purpose of delivering the pressed material to a dryer or other apparatus for further treatment. A deflector 92, shown in Figure 4, is bolted or otherwise suitably secured to flanges 90 at the top thereof and extends downward within the press, the lower portion of this deflector, designated 92a, being bent downward at an angle and having its end beveled and in contact with the spacing ring 19. Deflector 92 is shaped to fit snugly between the discs 18 and close the space therebetween. The material is delivered between the discs through the hopper 77 and, during rotation of the discs, the lower portions thereof are moved towards each other so that the material in the lower portion of the press is subjected to considerable pressure and, in the continued rotation of the discs, the pressed material is directed through the discharge opening 91 by means of the deflector 92, as indicated by the arrows in Figure 4, from certain of which arrows it will be noted that the rotation of the discs is counterclockwise as viewed in this figure. This operation of the press, broadly considered, is known in the art and need not be described in greater detail.

Each of the pressure discs 18 is provided, at its inner face, with a plurality of strainer plates. I have shown six plates for each disc, though the number of plates may be varied, within limits, as will be understood. Each of these plates comprises a body 94 and a screen 95, the plate in its entirety being designated 93. Body 94 extends from sealing ring 24, upon the outer edge of which the inner edge of body 94 seats, to the periphery of disc 18. Screen 95 conforms in shape to body 94 and is secured thereto in a suitable manner, as by means of rivets 96. The strainer plate thus constitutes a sector of the disc. At its inner face body 94 of the strainer plate is provided with a plurality of projections spaced sufficiently close together effectively to support the screen 95, these projections defining intercommunicating grooves from certain of which passages 97 extend through body 94 of the strainer plate. This assures that the water or liquid expressed from the solids of the material being treated will readily pass through the strainer plate. Body 94 of the strainer plate is also provided, in its outer face, with suitably disposed depressions and grooves, into certain of which the passages 97 open. These depressions are disposed to com-

municate with openings 98 through the discs 18. In this manner, the expressed liquid can readily pass through the discs onto flanges 46 from which it flows into the casing 10 and thence through the openings 51. The construction of the strainer plates and of the discs, with reference to the openings and passages therein, is, in general, known in the art and need not be described in greater detail.

10 Each of the strainer plates 93 is provided, at its outer face and adjacent each lateral edge thereof, with a lug 99 which fits into a groove 99a (Figure 4) formed in the inner face of disc 18 concentrically therewith. Each plate is further provided, inwardly of lugs 99, with two bolt openings 100 and a squared depression 101 extending about the respective openings. Depression 101 receives the correspondingly shaped head 102 of a bolt 103 passing through the plate and the disc, a securing nut 104 being screwed upon the outer end of the bolt. The strainer plates of the discs 18 are thus demountably secured upon the latter. The casing sections 11 are suitably provided with openings, normally closed by screw plugs 105 removably held in position in a known manner, so that access may be had to nuts 104 for removal therefrom of the bolts 103. After removal of nuts 104 the bolts 103 are removed, thus permitting removal of the strainer plates 93 through the openings 76 and 76a. In this manner, the strainer plates may be removed and replaced as required.

The strainer plates 93 are spaced apart, as shown in Figure 4, and each of the discs is provided with radial slots 106 extending from the periphery thereof to the spacing ring 19, disposed between the plates. Slots 106 accommodate vanes 107, each comprising an elongated head 108 and a shank 109 extending through the disc and projecting outward thereof. A trunnion bracket 110 is bolted to shank 109 of the respective vanes and carries rollers 111 which contact a cam track 112 at the inner face of each casing section 11. Guide rails 113, of Z-shape in cross section, are bolted to the cam track 112 and overlie the rollers 111, cooperating therewith and with the cam track for imparting the proper movement to the vanes.

In Figure 6 the cam track 112 is shown in face view and in Figure 7 a development of this track 50 is shown in section. Referring to these two figures, track 112 increases in thickness from A to B so as to present an upwardly or inwardly inclined surface between these two points, is of uniform thickness from B to C, presenting a horizontal or non-inclined surface between these latter points, decreases in thickness from C to D so as to provide a downwardly or outwardly inclined surface between these points, is provided with an abrupt downwardly or outwardly extending shoulder extending from D to E, and is of uniform thickness from E to A, so as to provide a non-inclined or horizontal surface between these two points. In Figure 6 the hopper 17, partition 19 and discharge opening 91 have been indicated by dot-and-dash lines for purposes of explanation. The pressure discs are rotated clockwise, as viewed in Figure 6, and it will be noted that the vanes, shortly after passing the partition 79, travel along the inclined surface A-B so as to be projected inward between the discs. The material to be pressed is delivered between the discs so as to maintain the space therebetween continuously filled. When the rollers 111 reach point B the vane is projected inward to its maxi-

mum extent and remains so projected until it reaches the point C. In the meantime, the preceding vane, the associated rollers 111 of which are traveling along the surface C-D, remains projected to approximately its maximum extent 5 so long as it remains at the lower portion of the casing. The vanes of the discs are arranged in pairs so disposed that the vanes of each pair, when projected, are in overlapping juxtaposed relation and effectively close the space between 10 the discs. In this manner the material at the lower portion of the casing, where the final pressing operation is performed, is confined within a compartment closed both radially and circumferentially of the discs to escape of the material. 15 This will be understood from Figures 3 and 5, showing the positions of the vanes at the lower portion of the casing, the latter figure showing two pairs of vanes in their fully projected and overlapping positions. By confining the material in this manner I effectively prevent escape 20 of material from between the discs at the area thereof where maximum pressure is exerted, which is the lower portion of the press, and assure efficient operation of the press even when handling excessively wet material. Further, confining the material in a closed compartment in this manner assures the presence between the pressing areas of the discs of a sufficient quantity 25 of material to assure that the pressed material 30 will not have a moisture content in excess of that required for most efficient subsequent treatment of the material, which is of considerable practical importance.

In the continued rotation of the discs the 35 rollers 111 travel down the shoulder D-E, thus completely retracting the vane before it reaches the deflector 92. The vane is held retracted during travel of the rollers 111 from E to A, that is, during travel of the vane from position E of 40 Figure 6, in advance of deflector 92, to position A of this figure, beyond partition 19. The movements of the vanes are timed with respect to rotation of the pressure discs, as above, and the maximum projection of the vanes is 45 such as to prevent objectionable contact of the vanes of either of the discs with the other disc. While the vanes are preferably so arranged as to be disposed in pairs in overlapping juxtaposed relation, when projected, they may be otherwise 50 suitably disposed within the broader aspects of my invention.

The discs proper 18 are of substantially conical shape, as previously stated, the central portions thereof, defined in part by the sealing rings 24, 55 being flat and normal to the axes of the hubs 17. During rotation of the discs they move toward and away from each other, being oppositely inclined, the minimum distance between the discs being at the bottom or lower portion of the press. 60 If the pressure applying surfaces of the discs were shaped in this manner, the portions of such surfaces at the lower portion of the press would define a space flaring radially of the discs toward the peripheries thereof and also flaring circumferentially of the discs from a plane extending transversely of this space centrally thereof, this plane passing through the points of the opposed surfaces which are a minimum distance apart in the rotation of the discs. This means that the 65 material being acted upon would be subjected to maximum pressure along a line extending radially of the discs, with the pressure decreasing in opposite directions from this line circumferentially of the discs, the pressure also decreasing radially 70 75

of the discs. This renders it difficult for the discs effectively to retain the material between them during the pressing operation, with the result that this material, if it contains a considerable amount of moisture, is apt to be merely displaced between the discs and not subjected to any effective pressure, particularly if the material is slippery or slimy in character, which is frequently the case. I avoid this difficulty by forming the strainer plates of the discs in a novel manner.

Referring to Figure 5, it will be noted that the respective strainer plates 93 increase in thickness from midpoint 93a thereof to each side 93b, the outer face of the plate being curved transversely to fit the corresponding area of disc 18, the inner face of this plate being flat and normal to the axis of rotation of the disc. The opposed pair of strainer plates carried by the opposed discs thus provide opposed pressure applying surfaces of considerable area approximating sectors of the discs, the surfaces of two opposed plates at the lower portion of the casing being disposed in parallelism circumferentially of the discs and also in substantial parallelism radially of the discs. The discs may thus be considered as provided with a plurality of flat contiguous pressure applying surfaces of considerable area, which surfaces, during rotation of the discs, are brought into parallelism and into position effective for applying maximum pressure to the material between these surfaces. In this manner the material operated upon is subjected to maximum pressure throughout a considerable area, rather than along a line only, as in presses of present type above referred to, which is conducive to high speed operation of the press and resulting increase in capacity, while eliminating slippage of excessively wet material when subjected to pressure between the discs. This, in conjunction with the vanes providing, with the discs and associated parts, closed compartments at the lower portion of the press, renders it possible to handle, with expedition and facility, materials of various sorts, even when such materials contain excessive amounts of moisture in such proportion as would render pressing thereof in rotary presses of ordinary type difficult or impossible. My invention comprehends setting the pressure discs at such an inclination that the space or compartment between the lower portions of these discs, in which the material is subjected to final maximum pressure, is of truly uniform width radially of the discs, though in many cases this is not necessary, but this space should not flare radially of the discs to any considerable extent.

I claim:—

1. In a press of the character described, a casing, two opposed discs mounted within said casing for rotation about oppositely inclined axes, means closing the space between the central portions of said discs and sealing the central portion of the respective discs, means for directly driving both of said discs in unison, radial vanes slidable through the respective discs in the direction of the axis thereof and spaced apart circumferentially of said discs, said vanes when projected closing the space between said discs, and means for projecting and retracting said vanes in timed relation to rotation of said discs, said vanes extending radially of said discs from said central portions to the peripheries thereof and said casing closing the space between said discs at the outer ends of the projected vanes.

2. In a press of the character described, a casing, two opposed discs mounted within said cas-

ing for rotation about oppositely inclined axes, means closing the space between the central portions of said discs and sealing the central portion of the respective discs, means for directly driving both of said discs in unison, a plurality of vanes slidable through the respective discs parallel to the axis thereof, said vanes extending radially of the discs from the periphery thereof to said closing and sealing means and cooperating with the latter and said casing and said discs, when projected, to provide compartments substantially corresponding to sectors of said discs and closed radially and circumferentially thereof, and means for projecting and retracting said vanes in timed relation to rotation of said discs. 10

3. In a press of the character described, a casing, two opposed discs mounted within said casing for rotation about oppositely inclined axes, means closing the space between the central portions of said discs and sealing the central portion of the respective discs, means for directly driving both of said discs in unison, a plurality of vanes slidable through the respective discs parallel to the axis thereof, said vanes extending radially of the discs from the periphery thereof to said closing and sealing means, the vanes of one disc being offset circumferentially thereof relative to the vanes of the other disc such that the vanes of said discs, when projected, are disposed in pairs with those of each pair overlapping and closing the space between said discs, and means for projecting and retracting said vanes in timed relation to rotation of said discs, said vanes when projected cooperating with said closing and sealing means and said casing to provide compartments substantially corresponding to sectors of said discs and closed radially and circumferentially thereof. 20

4. In a press of the character described, a casing provided at its sides with oppositely inclined inwardly projecting bearing sleeves, two opposed discs within said casing each having an outwardly projecting axial hub rotatably mounted on said sleeves, a tapered spacing member disposed between said discs and fixed to said sleeves, and sealing rings secured to said discs and bearing upon said spacing member, said sleeves being provided with means for admitting thereto liquid leaking past said rings and having drainage outlets. 30

5. In a press of the character described, a casing provided at its sides with oppositely inclined inwardly projecting bearing sleeves, two opposed discs within said casing each having an outwardly projecting axial hub rotatably mounted on said sleeves, a tapered spacing member disposed between said discs and fixed to said sleeves, and sealing rings secured to said discs and bearing upon said spacing member. 40

6. In a press of the character described, a casing provided at each side with a hub and an inwardly projecting sleeve concentric with and spaced from said hub, said hub and said sleeve being inclined downward and outward of said casing, two opposed discs within said casing each having an outwardly projecting axial hub, said hubs being rotatably mounted on said sleeves with their outer portions fitting into said casing hubs, a tapered spacing ring disposed between said discs and fixed to said sleeves, and sealing rings secured to said discs in sealing contact with said spacing ring, said sealing rings having flanges fitting into the inner ends of said sleeves. 50

7. In a press of the character described, two 75

- opposed perforated discs rotatable about oppositely inclined axes and having their opposed inner faces of conical formation, and strainer plates mounted upon the inner faces of said discs and defining pyramidal frusta with the plates respectively forming sectors thereof, the outer faces of said plates being curved conformably to the inner faces of said discs and the inner faces of said plates being flat.
8. In a press of the character described, two opposed perforated discs rotatable about oppositely inclined axes and having their opposed inner faces of conical formation, strainer plates mounted upon the inner faces of said discs and defining pyramidal frusta with the plates respectively forming sectors thereof, the outer faces of said plates being curved conformably to the inner faces of said discs and the inner faces of said plates being flat, the lateral edges of said plates being spaced apart and said discs having radial slots opening between adjacent plates, vanes slideable through said slots and between the plates in the direction of the axis of the respective discs, and means for projecting and retracting said vanes in timed relation to rotation of said discs.
9. In a press of the character described, two opposed discs rotatable about oppositely inclined axes, and means for rotating said discs in unison, the opposed faces of said discs being provided with flat surfaces of considerable area and extent circumferentially of said discs, said surfaces being inclined inwardly and radially of said discs at such an angle that a flat surface on one of

said discs is disposed in substantial parallelism with a flat surface on the other of said discs both radially and circumferentially of the discs, when said pair of surfaces are spaced their minimum distance apart in the rotation of said discs.

10. In a press of the character described, two opposed discs rotatable about oppositely inclined axes, and means for rotating said discs in unison, the opposed faces of said discs being provided with flat surfaces of considerable width circumferentially of the discs defining sectors of the respective discs, said surfaces being inclined inwardly and radially of said discs at such an angle that a flat surface on one of said discs is disposed in substantial parallelism with a flat surface on the other of said discs both radially and circumferentially of the discs, when said pair of surfaces are spaced their minimum distance apart in the rotation of said discs.

11. In a press of the character described, two opposed perforated conical discs rotatable about oppositely inclined axes, means for rotating said discs in unison, and plates mounted on the opposed conical faces of said discs and defining pyramidal frusta with the plates respectively forming sectors thereof, said plates being formed and arranged to present flat surfaces of considerable width circumferentially of the discs, a flat surface on one of said discs being disposed in substantial parallelism with a flat surface on the other of said discs, when said pair of surfaces are spaced their minimum distance apart in the rotation of said discs.

CHARLES F. SCHERER.
